ALBERT C. PAULSMEIER, OF ALAMEDA, CALIFORNIA, ASSIGNOR TO BYRON JACKSON IRON WORKS, OF SAN FRANCISCO, CALIFORNIA, A CORPORATION OF CALIFORNIA.

DEEP-WELL-PUMP-OILING SYSTEM.

1,169,994.

Specification of Letters Patent.

Patented Feb. 1, 1916.

Application filed May 12, 1914. Serial No. 838,105.

To all whom it may concern:

Be it known that I, ALBERT C. PAULSMEIER, a citizen of the United States, residing at Alameda, in the county of Alameda 5 and State of California, have invented new and useful Improvements in Deep-Well-Pump-Oiling Systems, of which the following is a specification.

This invention relates to centrifugal 10 pumps and pertains especially to a pressure feed lubricating system for deep-well pumps.

The purpose of the present invention is to provide a pressure feed lubricating system which is so constructed and connected with 15 a deep-well-pump that the shaft housing will be constantly filled with a lubrication which is maintained under a sufficient pressure to overcome or balance the outside water pressure, or the pressure created by 20 the water within the well casing, and thereby exclude water from the bearings while maintaining perfect lubrication; the pressure of the lubricant being greater than the water pressure under normal working conditions.

Another object of the invention is to provide a lubricating system of the character described, which is simple in construction and automatic in operation, and which is 30 provided with means for trapping and draining any water which might enter the casing.

Further objects will hereinafter appear.

The invention consists of the parts and 35 the construction and combination of parts as hereinafter more fully described and claimed, having reference to the accompanying drawings, in which the figure is a central, vertical section of a deep-well pump, 40 showing the application of the invention.

Referring to the drawing, A indicates a deep-well pump of the centrifugal type; 2 the discharge pipe; 3 the pump shaft revolved by suitable means not shown; 4 a 45 tube which is inside of and concentric with and spaced from the pipe 2, and which surrounds the shaft and bearings 5; the spiders 5' serving to space properly the two pipes 2—4 and maintain the proper alinement of the shaft; 6 is a suitably supported annular shell arranged at the top of the well and enclosing an oil chamber 7, and also supporting a thrust bearing 8. Connecting chamber 7 with a suitable source of oil supply under 55 pressure, as the oil reservoir 10, is a pipe 11.

with a valve 12. The upper coupling 13 for pipe or shaft tube 4 is fixed tight in the bottom of the chamber 7, and is extended a considerable distance up into the chamber 7 so as to provide a rim over-flow oil feed, 60 as later described. This coupling 13 also forms a bearing for the pump shaft 3, and with the several other bearings 5 is provided throughout the pump with oil ducts 14 which permit the oil to be forced down 65 through the tube 4 from one bearing to another, and finally fill the tube 4. Except for this counter-thrust of oil in the pipe or shaft tube 2 no attempt is made to prevent the well water entering the tube 2 under or 70 through the lower shaft bearing, which objection is overcome by the employment of a foot valve 22 in the bottom suction, as later described. In the absence of the foot valve 22, when the pump is at rest and the oil supply turned off, the tube 2 may fill with water 75 to the level of the well. It is only when the pump is working that the present invention comes into service.

As previously stated in one of the objects 80 of the invention, it is desired to fill the tube 4 with a lubricant, and to maintain a sufficient pressure on same to overcome the exterior water pressure to which the several pipe joints are exposed. This is accomplished in the present instance by placing a piston member 15 within reservoir 10 which is actuated by and adjustable weight 16 85 mounted upon a lever 17 pivotally secured, as at 18, on one side of the reservoir; the 90 weight of the lever being transmitted to the piston through means of link 19.

From the foregoing description it can now be seen that any suitable pressure may be created in the reservoir by adjusting the 95 position of weight 16. The oil under pressure is then delivered through pipe 11, and the volume or flow of same is controlled by valve 12. Chamber 7, together with connected tube 4, is subject to a pressure equal 100 to that in reservoir 10, and this is regulated so as to balance the exterior water pressure to which the tube 4 is exposed. Any water that might otherwise tend to leak around or through any of the pipe couplings and enter either tube 4 or chamber 7 is prevented 105 by the slight excess of pressure maintained in chamber 7 and tube 4. If any water should enter chamber 7 it will be trapped in the lower portion of chamber 7, and be 110

- drained off from time to time through valve 20; a suitable form of gage glass being connected with same for the purpose of detecting the presence of water within chamber 7.
- 5 Pressure upon the oil within the reservoir 10 may be created by piston 15 and weight 16, as shown, or by forcing air into the closed tank partly filled with oil.
- In order to balance oil and water pressures, even when the pump is standing still and prevent oil entering the well, or vice versa, prevent the well water entering the shaft tube 2, a foot valve 22 is placed within the suction of the pump, thereby maintaining full water pressure in the pump proper and the space formed by the two concentric tubes, which will be equal to the oil pressure when the inner tube is completely filled up to the top, any oil will thus be prevented from leaking through the packing and thereby be wasted. The system will in this case not only operate perfectly when the pump is in operation, but also will prevent the waste of oil when standing still.
- 25 Furthermore, it will positively prevent the water from entering the inner tube, so long as the inner tube is completely filled with oil, which condition may be easily maintained.
- 30 The lubricating system constructed and connected as here shown is simple in construction and automatic in operation, as it is only necessary to fill reservoir 10 from time to time, turning valve 12 on when the 35 pump starts and closing it when the pump stops.
- The materials and finish of the several parts of the apparatus are such as the experience and judgment of the manufacturer may dictate.
- 40 Having thus described my invention, what I claim and desire to secure by Letters Patent is:
1. In a centrifugal pump, the combination with the shaft, of a tube inclosing the same, an inclosed oil receptacle, shaft bearings in the tube, the uppermost of said bearings projecting into the receptacle and having an overflow duct to bring the tube and receptacle into communication, and the other bearings in the tube having ducts through which oil may pass, and means for maintaining at will an oil pressure in the receptacle and tube and throughout the 55 length of the latter.
  2. In a centrifugal pump, the combination with a shaft, of a tube inclosing same, a discharge pipe connected with the pump surrounding said tube, a check valve on the suction end of the pump to maintain a constant head of water in the discharge pipe, and means for maintaining an oil pressure in the shaft tube sufficient to exclude the entry of well water therein.
  3. In combination with a centrifugal pump and its shaft, a member surrounding said shaft, a discharge pipe connected with the pump and surrounding said member, means adjacent the suction end of the pump to maintain a constant head of water in the discharge pipe, and means for maintaining an oil pressure in the member sufficient to exclude the entry of well water therein.
  4. In combination with a centrifugal pump having an incased line shaft, a sealed oil receptacle into which the shaft extends and automatic means for maintaining the oil in said receptacle and throughout the length of the shaft casing at a predetermined constant pressure sufficient to exclude entry of well water into the shaft casing.
  5. In combination with a centrifugal pump having an incased line shaft, a sealed oil receptacle into which the shaft extends, automatic means for maintaining the oil in said receptacle and throughout the length of the shaft casing at a predetermined constant pressure sufficient to exclude entry of well water into the shaft casing, and means for enabling any water which may enter the receptacle to be drained therefrom.
  6. In combination with a centrifugal pump having an incased line shaft, a sealed oil receptacle into which the top end of the shaft extends for providing a head of oil and for feeding oil into the shaft casing, an oil reservoir communicating with said oil receptacle, and means associated with the reservoir for automatically and constantly maintaining a predetermined pressure on the oil whereby to maintain such pressure in and throughout the shaft casing to prevent the entry of well water into the casing.

In testimony whereof I have hereunto set my hand in the presence of two subscribing witnesses.

ALBERT C. PAULSMEIER.
